CLAIM

The ornamental design for a carbon wrench, as shown
and described.

DESCRIPTION

FIG. 1 is a perspective view of the end of the inventive
carbon wrench;

FIG. 2 is a plan view of the end of the wrench, looking
from the left-hand end, as viewed in FIG. 1;

FIG. 3 is a plan view of the end of the wrench, looking
from the right-hand end, as viewed in FIG. 1; and

FIG. 4 is a side elevation view of the inventive wrench,
with a handle (which does not constitute part of the
invention) shown in dot-dashed lines.
